UNITED STATES PATENT OFFICE.

CURRY O. WALPER, OF DETROIT, MICHIGAN, ASSIGNOR, BY MESNE ASSIGNMENTS, TO UNITED STATES GYPSUM COMPANY, OF CHICAGO, ILLINOIS, A CORPORATION OF ILLINOIS.

WALL BOARD.

Application filed March 15, 1928. Serial No. 94,795.

In building construction employing wall boards many circumstances are often met with which render the application of the boards somewhat difficult and often under the present methods of application result in a very unsatisfactory condition after the work is completed, due to the fact that the boards are not securely nailed to the supports or do not overlap the supports to a sufficient extent to provide an adequate bearing for the boards. Sometimes studdings over which the boards are laid are not in a common plane so that bending of the boards must be resorted to with consequent strain on the edges of the boards, and if the nailing is very near to such edges, as is often necessary, a weakness in the construction may result and the boards be liable to break away or loosen from their supports.

The present invention has for its object to provide a very simple device for application to or use in connection with wall boards for the purpose of strengthening the security of the boards when nailed in position, for rendering it easier to secure boards to their supports under conditions which ordinarily render effective nailing difficult and which will admit of the boards being nailed to their supports in a manner very desirable under some conditions but not feasible without the provision of special means to render such nailing effective.

The invention further contemplates the provision of clips adapted to be utilized in combination with the nails used in the securing of wall boards to their supports, in such manner that an effective engagement of the boards by the nails may be obtained in cases where it is necessary that such nails be close to the edges of the boards and even in cases where the nails do not pass through the boards at all, but are adjacent such edges.

Still further objects subsidiary to or resulting from the aforesaid objects, or from the construction or operation of the invention as it may be carried into effect, will be apparent as the said invention is hereinafter further disclosed.

In carrying the said invention into effect, I may provide U-shaped clips or channel

members, preferably of metal, adapted to embrace the edges of wall boards at nailing points whereby nails may be passed through the said clips and the portion of the board engaged thereby into a support; or the nails may be driven into such support exterior to the clip but adjacent the same whereby the head of the nails will engage such clips and effect the securing of the board in the desired manner. Such clips may also be utilized on the support for increasing the supporting area presented to the boards.

All of which is more particularly described and ascertained hereinafter, by way of example, having reference to the accompanying drawing, wherein—

Figure 1 is a fragmentary perspective view illustrating the application of the invention to a wall construction;

Figure 2 is a transverse section of a stud- 70 ding and wall board secured thereto in the improved manner;

Figure 3 is a detail perspective view of one of the clips, and

Figure 4 is a perspective view illustrating 75 the manner of securing a board by nailing outside the edge of the board.

Similar characters of reference indicate similar parts in the several figures of the drawing.

1 indicates studding, and 2 wall boards applied thereto. To the nailing edges of such boards I propose to apply clips 3 preferably of metal and in the form of channel members, the sides 4 of which are adapted to extend 85 over the faces of the board and may be perforated as at 5 to facilitate the passage of nails 6 therethrough although in some cases where the nature or thickness of the metal does not require it such perforations may 90 be omitted.

It often happens in the application of wall boards to studding that, due to variations in the spacing of the studding, some of the boards do not overlap such studding to an extent which admits of solid nailing, the nails having to be driven into the wall board closer to the edge thereof than is good practice, and insecure or otherwise unsatisfactory construction results.

By applying my improved nailing clips to such edges and driving the nails through these clips into the studding the board is secured much more firmly as will be quite obvious, and the nails may be driven into the supports much harder than would be otherwise possible without damaging the edges of the board. These advantages are also attainable even where the boards do overlap the supports in a normal manner, as the reinforcing nature of the clips will render the nailing more effective and permit the nails being driven home with more force than is ordinarily possible.

As shown in Figure 4 the nails may not necessarily be passed through the clip, the said illustration indicating the nail 6 as being driven into the studding exterior to the clip but in such manner that the head 7 of the nail engages the angular portion of the clip whereby the said clip may be quite firmly held between the head of the nail and the studding with consequent attachment of the board 2 to the studding. This is especially advantageous wherein the studding is very narrow and the overlapping of the boards thereon is such that it does not lend itself to nailing through the edges of the boards, in which case the nails may be merely passed between the adjacent edges of the boards which are provided with clips of the type referred to beneath the heads of the nails.

Also, where insufficient support is offered by the studding to the edges of the boards, I may utilize some of the clips for the purpose of increasing the effective area of such support as indicated in Figure 1, wherein 3^a indicates clips nailed to the sides of the said stud so that they may bear against the back of the boards for such purpose.

Clips of this description may be used to facilitate nailing of wall boards and afford support, reinforcement and protection to such boards under many conditions met with in building construction, and the added expense to the cost of such construction is almost negligible whilst the advantage gained by the use of clips is considerable.

It will be readily understood that these clips may be made in many shapes, weights and sizes to suit certain classes of work or material to which they are to be applied, and I do not wish to limit myself to the exact form shown by way of illustration.

What I claim is:—

1. In a wall construction, a support, a wall board applied to said support with its edge overlapping said support, a clip engaging said edge and the adjacent faces of said board and abutting said support and a nail driven through said clip and into said support.
2. In a wall construction, a support, a board wall applied to said support with its edge overlapping said support, a clip engaging

said edge and the adjacent faces of said board and abutting said support, and a nail driven into said support and fixing said clip thereto.

In testimony whereof I affix my signature.
